CLAIM

The ornamental design for audio system, as shown and described.

DESCRIPTION

1. Audio system
2. Sound bar
3. Subwoofer
4. Speaker
- 1: Perspective
- 2.1 : Perspective
- 2.2 : Front
- 2.3 : Back
- 2.4 : Left
- 2.5 : Right
- 2.6 : Top
- 2.7 : Bottom
- 3.1 : Perspective
- 3.2 : Front
- 3.3 : Back
- 3.4 : Left
- 3.5 : Right
- 3.6 : Top
- 3.7 : Bottom
- 4.1 : Perspective
- 4.2 : Front
- 4.3 : Back
- 4.4 : Left
- 4.5 : Right
- 4.6 : Top
- 4.7 : Bottom

(Continued)

Reproduction 1 shows an embodiment of an audio system, which includes a sound bar, a speaker and a subwoofer; Reproductions 2.1-2.7 are drawings showing an embodiment of the sound bar; Reproductions 3.1-3.7 are drawings showing an embodiment of the subwoofer; and, Reproductions 4.1-4.7 are drawings showing an embodiment of the speaker. The present product is used for playing audio. The broken lines shown in the drawings represent unclaimed portions of the article and form no part of the claimed design.
